UNITED STATES PATENT OFFICE.

CHARLES B. DAVIDSON, OF ST. JOSEPH, MISSOURI.

CHURNING APPARATUS.

SPECIFICATION forming part of Letters Patent No. 234,253, dated November 9, 1880.
Application filed August 27, 1880. (Model.)

To all whom it may concern:

Be it known that I, CHARLES BRUETT DAVIDSON, of St. Joseph, in the county of Buchanan and State of Missouri, have invented 5 a new and Improved Churning Apparatus, of which the following is a specification.

Figure 1, Sheet 1, is a front elevation, partly in section, of the improvement. Fig. 2, Sheet 1, is a sectional side elevation. Fig. 3, Sheet 10 2, is a side elevation. Fig. 4, Sheet 1, is a plan view of the dasher.

Similar letters of reference indicate corresponding parts.

The object of this invention is to furnish a 15 churning apparatus so constructed as to give a very rapid motion to the dasher by a slow movement of the driving-power.

A represents the body, and B the cover, of 20 a churn. To the cover B is attached a vertical frame, C, to receive the operating mechanism.

D is the dasher-shaft, to which are attached 25 two or more cross-bars, E, in such positions that as the said dasher-shaft D is revolved the ends of the said cross-bars E will pass between inwardly-projecting arms F, attached to the upright bars a, placed against the inner surface of the sides of the churn-body A. The lower ends of the bars a are inserted in 30 sockets in the bottom of the churn-body A, and their upperends are inserted in slots in the ends of the cross-bar b, which extends across the churn-body A, and has a hole formed through its center, through which the dasher-shaft D passes. The hole through the cross-bar b is 35 made larger than the dasher-shaft D, so that the said cross-bar will not interfere with the revolution of the dasher-shaft. By this construction the revolution of the cross-bars E, in 40 connection with the stationary arms F, will throw the milk into violent agitation, and will bring the butter in a very short time. The lower end of the dasher-shaft D revolves in a socket or step in the center of the bottom of the 45 churn-body A. The upper end of the dasher-shaft D, or a tenon formed upon the said upper end, fits into a cavity in the lower end of the shaft G, where it is secured detachably by a pin or other suitable means. The shaft G passes

through a hole in the center of the churn-cover B and revolves in bearings in the lower cross-bars of the frame C.

To the upper end of the shaft G is attached a small beveled-gear wheel, H, the teeth of which mesh into the teeth of a large beveled-gear wheel, I, attached to the shaft J. The shaft J revolves in bearings in the upright bars of the frame C, and to the said shaft is attached a small gear-wheel, K, the teeth of which mesh into the teeth of the large gear-wheel L attached to the shaft M. The shaft M revolves in bearings in the upright bars of the frame C, and to the said shaft is attached the end of a spring, N, which is coiled around the said shaft M, and its other end is attached to 65 the top cross-bar of the frame C. The large gear-wheel L is loose upon the shaft M, and to it is pivoted a pawl, O, which is held forward by a spring, P, attached to the said wheel L. The pawl O engages with the teeth of a 70 ratchet-wheel, Q, attached to the shaft M, so that the shaft M will carry the gear-wheel L with it when turned forward, but may be turned back to coil the spring N without revolving the said gear-wheel. One end of the shaft M 75 projects, and is squared to receive a key for winding up the spring N. With this construction the uncoiling of the spring N will give a very rapid motion to the dasher D, E, and will bring the butter in a very short time. 80 If desired, the spring N may be replaced by an equivalent weight, the descent of which will give motion to the churn-dasher; or a crank may be attached to the projecting end of the shaft J, and motion given to the dasher 85 by hand, the small gear-wheel K being moved upon the shaft J to throw it out of gear with the gear-wheel L upon the shaft M. The other end of the shaft J projects, and to it is attached a large pulley, R, which is made heavy 90 to adapt it to serve as a fly-wheel to give steadiness of motion to the dasher. Around the pulley R passes a band, S, which also passes around a small pulley, T, attached to the projecting end of a shaft, U. The shaft U 95 revolves in bearings in the outer ends of arms or brackets V, attached to the uprights of the frame C.

To the shaft U is attached a hub, W, to which are attached two or more radial arms or spokes, X.

To the outer ends of the arms or spokes X 5 are attached wings Y, which act upon the air, and thus retard and give steadiness to the movement of the mechanism. The arms or spokes X should be adjustable, so that the wings Y may be adjusted parallel with or at 10 an angle to the shaft U, according as it is desired that the mechanism should have a slower or a faster movement.

To the end of the shaft J is attached a short crank, c, to the crank-pin of which is pivoted 15 the upper end of a connecting-bar, d. The lower end of the bar d has a number of holes formed through it to receive the bolt e, to which is pivoted the end of a lever-spring, f, or the handle g, attached to the said end of the 20 spring f. The spring f is made flat and long,

and its other end is attached to the upper end of a post, h, attached to the floor or platform upon which the churn A stands.

With this construction the churn can be operated by working the lever-spring f. 25

Having thus described my invention, what I claim as new, desire to secure by Letters Patent, is—

In a churning apparatus, the combination, with the dasher D E, the shafts G J, and the 30 gear-wheels H I, of the crank c, connecting-bar d, and straight lever-spring f g, substantially as herein shown and described, whereby a rapid motion can be given to the dasher, as set forth.

CHARLES BRUETT DAVIDSON.
